Primary Examiner — John Windmuller*Assistant Examiner* — Steven Czyz(74) *Attorney, Agent, or Firm* — Erin Collins; Stacy H. Combs(57) **CLAIM**

The ornamental design for a dispenser, as shown and described.

DESCRIPTION

FIG. 1 is a perspective view of a dispenser showing our new design;

FIG. 2 is a top plan view thereof;

FIG. 3 is a bottom plan view thereof;

FIG. 4 is a left side view thereof;

FIG. 5 a right side view thereof;

FIG. 6 is a front end view thereof; and,

FIG. 7 is a rear end view thereof.

The broken lines depict portions of the article that form no part of the claimed design.
